UNITED STATES PATENT OFFICE.

OTTO W. SIEBERT AND ORA N. TURNER, OF TEMPLETON, MASSACHUSETTS; SAID TURNER ASSIGNOR TO BAY STATE METAL WHEEL COMPANY, OF TEMPLETON, MASSACHUSETTS, A CORPORATION OF MAINE.

CONVERTIBLE BABY-CARRIAGE.

1,167,439.

Specification of Letters Patent. Patented Jan. 11, 1916.

Application filed June 16, 1915. Serial No. 34,371.

To all whom it may concern:

Be it known that we, OTTO W. SIEBERT and ORA N. TURNER, citizens of the United States, and residents of Templeton, in the 5 county of Worcester and State of Massachusetts, have invented certain new and useful Improvements in Convertible Baby-Carriages, of which the following is a specification.

10 The object of the present invention is to provide an improved baby carriage which may be converted into a bassinet.

The invention comprises a body which is 15 usable either as a car or body of a baby carriage or as a bassinet, said body having legs arranged to be folded against its bottom when it is mounted on the running frame of the carriage.

One improved feature of the invention is 20 the arrangement of the legs whereby they are adapted to be lapped when folded against the bottom of the body and whereby they are adapted, when unfolded, to have a width of base greater than the width of 25 the body or bassinet, and a length of base greater than the length of the bottom of the body.

Another improved feature is the means 30 for detachably connecting the car or body to the running frame of the carriage, the said means permitting the car or body to be arranged with either end at the front of the running frame.

Other improved features are illustrated 35 by the accompanying drawings and are hereinafter described and claimed.

On the drawings: Figure 1 represents a side elevation of a baby carriage embodying the present invention, the canopy top being 40 represented in three different positions. Fig. 2 represents a vertical cross section, on a larger scale, through the structure intersected by line 2—2 of Fig. 1. In this figure the folding legs are represented in folded 45 position by solid lines and are represented in open position by dotted lines. Fig. 3 represents a bottom plan view of the car or body, with the legs in folded position, the figure also including the structure intersected by line 3—3 of Fig. 1. Fig. 4 represents a side elevation of the car or body converted for use as a bassinet. Fig. 5 represents an end elevation of the structure shown by Fig. 4.

The same reference characters indicate the 55 same parts wherever they occur.

The body 10, as shown, is made of wicker-work built upon a suitable framework which includes a flat rigid bottom frame or foundation 21. For some purposes of this invention the body is symmetrical, having flat sides, a flat bottom, and scow-shaped ends projecting a considerable distance beyond the ends of the flat bottom. The matter of shape renders the body appropriate for the car of 60 a baby carriage as shown by Fig. 1 and for a bassinet as shown by Figs. 4 and 5.

The running frame of the carriage includes front wheels 11, and axle 12 therefor, rear wheels 13, a rear axle 14, longitudinal 70 reaches such as that indicated at 15 connecting the axles, and push-bars such as that indicated at 16. The running frame carries a body-supporting structure made in two sections each comprising leaf springs 17 and 75 18. The springs 18 are made in pairs, each pair being made from a single strip of spring steel, the spring portions 18, 18, being connected at their upper ends by an intermediate portion 19 which is substantially 80 straight and horizontal, excepting that it has an offset portion 19' to provide clearance for the latching device, hereinafter named.

For the purpose of mounting the body upon the platform afforded by the portions 85 19, the bottom (frame 21) of the body is provided with two pairs of saddles permanently affixed and each having a pair of ears 20. The ears 20 are arranged to straddle the portions 19 as shown by Figs. 2 and 3. 90 The body is provided with fastening devices of well known construction, each of which comprises a swivel head 22. The portions 19 are provided with elongated holes or slots 23 through which the heads 22 may be 95 passed. The said heads are elongated, and are intended to be turned to register with the holes or slots 23 to permit attaching and detaching the body, and to be turned to the positions shown by Figs. 2 and 3 to lock the 100 body to the portions 19. The fastening devices, being symmetrically arranged, enable the body to be attached with either end toward the front of the running frame.

A canopy top or hood is indicated at 105 25. It has flat sides 26 and a segmental cylindric portion 27 connecting the sides. The body is provided with fixtures 28

and with clamping bolts 29 and wing nuts 30 for attaching the top or hood to the body and for holding the top or hood in various angular positions relatively to the body. The top or hood is provided with shanks 31 which embrace the bolts 29 and swing thereon. The fixtures 28 are fastened to the sides of the body midway between the ends of the latter to enable the top or hood to coöperate with both ends of the body in the same manner. The proportions of the body and hood are such that the latter may occupy either of the two extreme positions indicated by dotted lines in Fig. 1, in which positions the ends of the body and hood are nested, thus leaving the top of the body uncovered and unobstructed, with substantially the same result as though the top or hood were collapsible. The reversibility of the arrangement of the body relatively to the running frame, and the reversibility of the hood relatively to the body, is due to the symmetrical shape of the body and to the symmetrical arrangement of the pivot members 29 relatively thereto.

The body 10 is provided with legs which are pivotally attached to its bottom so that they may be folded against the bottom, as shown by Figs. 2 and 3, when the body is upon the running frame. The legs are indicated at 32, and in the present instance there are two pairs of them, each pair being made from a single continuous piece of stock, preferably metal tubing. The end portions 33 of each said piece of stock are connected by pivot members 34 to fixtures 35 fastened to the bottom of the body. The intermediate portions 36 of said pieces of stock connect the two legs of each pair and coöperate with latching devices 37 to keep the legs in operative or unfolded position when the car or body is to be used as a bassinet. (See Figs. 2, 4 and 5). As shown by Fig. 2 the latching devices 37 are mounted upon a common pivot member 38, the latter being carried by a sheet-metal fixture 39 fastened to the bottom of the body. Each device 37 has a socket 40 at its outer end, said sockets being formed to receive the connecting portions or bars 36 of the legs, as represented by dotted lines in Fig. 2. The extremities 41 of the latching devices 37 are turned inwardly toward pivot member 38 to form channels through which the portions 36 must pass in order to enter the sockets 40. The free ends of the latching devices 37 are normally raised by suitable spring means to the positions represented by solid lines in Fig. 2, the latching devices being arranged to underlie the portions 36 so that they will be automatically depressed by the portions 36 as the legs are unfolded. It is thus assured that the portions 36 will enter the channels formed by the extremities 41 and that the latching devices will be automatically

lifted by their spring means to embrace the portions 36 as represented by dotted lines in Fig. 2. In the present instance a single torsion spring is arranged to act upon both latching devices 37, said spring 70 having a helical portion 42 surrounding the pivot member 38 and having hooks 43 at its ends engaged respectively with the two latching devices. When the legs are folded as shown by Figs. 1, 2 and 3, they are held so by one of the latching devices, which one depending upon the order in which the legs are folded.

As shown by Figs. 3 and 4, the legs of each pair diverge from the fixtures 35 by 80 which they are connected to the body. This diverging relation affords a length of base greater than the length of the bottom frame 21, and also enables the legs of one pair to cross those of the other pair when the legs 85 are folded (see Fig. 3), the legs being thus caused to clear the fixtures 35 so that they may fold into contiguous relation with the bottom of the body. This arrangement of the legs also causes the legs to clear the body-supporting structures 18, 19, which are carried by the running frame. When folding the legs, the first pair (which may be either pair) will fold into contact with the bottom of the body, and the second pair 90 will fold into contact with the first pair, the latching device for the latter pair automatically following the portion 36 of the latter to keep the legs in folded position.

When the legs are open in body-supporting position, their lower ends are spread apart beyond the perpendicular planes of the sides of the body, as shown by Fig. 5, thus affording a sufficient width of base.

We claim:

1. The combination with a running frame, and a body-supporting structure carried thereby, of a body, means arranged to fasten said body to said structure, said means being adjustable to permit detaching said body from said structure, two pairs of body-supporting legs arranged under said body and pivotally connected thereto so as to fold laterally against the bottom of said body, the free ends of said legs being movable beyond the perpendicular planes of the sides of said body, to support the body, and means carried by said body and arranged to latch said legs in body-supporting position.

2. In combination, a running frame, two separated body-supporting elements carried thereby, a detachable body adapted to rest upon said elements, two pairs of body-supporting legs, two pairs of fixtures affixed to and projecting downwardly from the bottom of said body, and pivotal means connecting said legs and said fixtures below the bottom of said body, said fixtures being arranged to set between said body-supporting elements, said legs being arranged to fold

upwardly into crossed relation under said body and to project beyond the longitudinal and transverse lines in which said fixtures are arranged.

5. 3. In combination, a running frame, body-supporting means including a platform carried by said running frame, a detachable body adapted to rest upon said platform, two pairs of body-supporting legs, and pivotal connections connecting said legs to the bottom of said body, said legs being arranged to fold upwardly into crossed relation under said body, the free ends of said legs being offset from said pivotal connections beyond the ends of said platform whereby said legs are caused to clear said platform when the legs are folded.

4. A baby carriage body or bassinet having two pairs of legs, and pivotal means connecting said legs to said body, said pairs of legs being arranged to fold upwardly into crossed relation under said body, said pairs

of legs being foldable in either order, the first pair so folded, according to either order, being foldable against the bottom of 25 said body, and the latter pair so folded being foldable against the first pair.

5. A baby carriage body or bassinet having two pairs of legs, pivotal connections connecting said legs with said body, said 30 legs being arranged to unfold to body-supporting position and to fold upwardly under said body, a bar connecting the legs of each pair to cause the legs of each pair to move in unison, and two spring-pressed 35 devices mounted on the bottom of said body to coact respectively with said bars, said devices being arranged to hold said pairs of legs in body supporting position and in folded position as the case may be. 40

In testimony whereof we have affixed our signatures.

OTTO W. SIEBERT.
ORA N. TURNER.
